UNITED STATES PATENT OFFICE.

PERLEY P. BELT, OF FREDONIA, KANSAS.

REGULATOR FOR DYNAMO-ELECTRIC MACHINES.

SPECIFICATION forming part of Letters Patent No. 433,269, dated July 29, 1890.

Application filed April 9, 1890. Serial No. 347,205. (No model.)

To all whom it may concern:

Be it known that I, PERLEY P. BELT, of Fredonia, in the county of Wilson and State of Kansas, have invented a new and Improved 5 Regulator for Dynamo-Electric Machines, of which the following is a specification, reference being had to the annexed drawings, forming a part thereof, in which—

Figure 1 is a side elevation of a dynamo 10 with my improved regulator applied thereto. Fig. 2 is a longitudinal section of the regulator on an enlarged scale. Fig. 3 is a transverse section taken on line *x x* in Fig. 2. Fig. 4 is a transverse section taken on line *y y* in 15 Fig. 2. Fig. 5 is a side elevation of the commutator-supporting sleeve. Fig. 6 is a side elevation of the piston of the rotary dash-pot, showing the inner surface of the cover; and Fig. 7 is a side elevation of the dash-pot, 20 showing the abutments in full lines and the piston in dotted lines.

Similar letters of reference indicate corresponding parts in all the views.

The object of my invention is to construct 25 an automatic regulator for dynamo-electric machines, in which the current delivered by the machine is made to shift the commutator-cylinder on the armature-shaft, and thus vary the output of the machine.

My invention consists in the combination, 30 with a dynamo-electric machine, of a commutator-cylinder mounted upon a sleeve placed on the armature-shaft and adapted to move through a quarter of a revolution, a 35 pulley mounted upon the sleeve and connected by a belt with an electric motor in the main circuit of the dynamo, a spring connected with the armature-shaft and commutator-supporting sleeve, and arranged to hold 40 the commutator cylinder forward to the point of maximum output, a pair of brushes making contact with the commutator-cylinder, a rotary dash-pot carried by the armature-shaft and having a piston connected with the commutator-cylinder, and the electric connections 45 between the commutator-bars and sections of the armature, all as will be hereinafter more fully described.

The dynamo A is of ordinary construction, 50 except that its armature-shaft B is prolonged beyond the bearing *a* and made tubular to

receive the wires leading from the sections of the armature C. Upon the tubular armature-shaft B is mounted a sleeve D, upon one end of which is secured the commutator-cylinder 55 E. Upon the opposite end of the sleeve is secured a pulley F, and to this pulley is attached one end of a volute spring *b*, the opposite end of which is connected with the armature-shaft B. In the sleeve D, between the pulley 60 F and the commutator-cylinder E, is formed a transverse slot *c*, which extends through a distance about equal to one-quarter of the circumference of the sleeve. A screw *d* extends through the slot *c* and into the armature-shaft B and serves to limit the movements 65 of the sleeve D on the armature-shaft. The spring *b* is arranged to hold the commutator-cylinder E forward in the direction in which it revolves.

The bars *e* of the commutator-cylinder E are connected with the sections of the armature C by the flexible wire cords *f* and the wires *g* extending through the tubular shaft B. The bearing *a* of the shaft B is prolonged 75 outward, forming a sleeve *h*, upon which is placed the yoke G, carrying the commutator-brushes H, which bear upon the commutator-cylinder E.

Upon the end of the tubular armature-shaft 80 B is secured a rotary dash-pot I, formed of the cylinder *i*, provided with the abutments *j*, the centrally-apertured cap *k*, and the piston *l*, provided with wings *m* and mounted upon the shaft *n*, passing axially through the 85 cylinder *i*. To the shaft *n* is secured a yoke *o*, which is connected with the commutator-cylinder E by rods *p*.

On the top of the dynamo A is mounted an electric motor J, having an armature-shaft *q*, 90 upon which is mounted a pulley *r*. The belt *s* passes around the pulley *r* of the motor and around the pulley F on the armature-shaft of the dynamo. The motor J is preferably provided with the ordinary well-known Siemens 95 H-armature. The said motor is connected with the dynamo, so that the current passing through it tends to revolve the armature of the motor in a direction opposite to that in which it is revolved by the belt *s*. So long as 100 the current in the outside circuit of the dynamo is normal the armature of the motor J

is revolved through the belt *s*, and the commutator-cylinder *E* is held upon the armature-shaft to the position for the normal output of the current. When the current in the external circuit increases, the strength of the field-magnet in the motor *J* is also increased and a greater drag is produced upon the armature, thereby holding back the pulley *F*, sleeve *D*, and commutator-cylinder *E* in opposition to the force of the spring, thereby changing the position of the commutator-cylinder *E* relative to the position of the sections of the armature *C*, thus diminishing the output of the current. When the current weakens in the external circuit, the power of the field-magnet of the motor over its armature is lessened, its drag upon the pulley *F* and commutator-cylinder *E* is reduced, and the spring *b* moves forward the commutator-cylinder *E* toward the position of maximum output. The dash-pot *I* upon the end of the armature-shaft being filled with some resisting medium—such as glycerine, alcohol, or even air—modifies the movements of the commutator-cylinder *E* and prevents vibrations and sudden changes in its position.

The form of the armature used in the motor *J* is such as to cause a slightly-uneven action, owing to the approaching and receding of the poles of the armature toward and away from the poles of the field-magnet. This periodic resistance insures the accurate working of the commutator-cylinder under slight changes of the current.

Having thus described my invention, I claim as new and desire to secure by Letters Patent—

1. In a regulator for dynamo-electric machines, the combination, with a dynamo provided with a movable commutator-cylinder, of an electric motor connected with the com-

mutator-cylinder and arranged in the dynamo-circuit, so as to tend to revolve by the current in a direction opposite to the rotary motion imparted to it by connection with the commutator-cylinder, substantially as specified. 45

2. In a regulator for dynamo-electric machines, the combination, with a commutator-cylinder movable on the armature-shaft and provided with a spring-connection with the armature-shaft, of an electric motor connected mechanically with the commutator-cylinder and electrically with the dynamo, so as to tend to turn the motor and commutator-cylinder in a direction opposite to that of the armature-shaft, substantially as specified. 50

3. In a regulator for dynamo-electric machines, the combination, with the commutator-cylinder provided with a spring-connection with the armature-shaft, of a rotary dash-pot for modifying the movements of the commutator-cylinder, substantially as specified. 55

4. In a regulator for dynamo-electric machines, the combination, with the commutator-cylinder movable on the armature-shaft, of a motor connected mechanically with the commutator-cylinder and electrically with the dynamo and adapted to offer an irregular resistance to the rotation of the commutator-cylinder, substantially as specified. 60

5. The combination of the dynamo *A*, provided with the tubular armature-shaft *B*, the sleeve *D*, mounted upon the armature-shaft, the commutator-cylinder *E* and pulley *F*, carried by the sleeve, the spring *b*, the flexible connections *f*, the motor *J*, and belt *s*, substantially as specified. 75
